UNITED STATES PATENT OFFICE.

JAMES W. GRIER, OF WILKINSBURG, PENNSYLVANIA.

COVER-LOCKING EAR FOR PAILS.

SPECIFICATION forming part of Letters Patent No. 690,104, dated December 31, 1901.

Application filed June 11, 1901. Serial No. 64,061. (No model.)

To all whom it may concern:

Be it known that I, JAMES W. GRIER, a citizen of the United States, residing at Wilkinsburg, in the county of Allegheny and State of Pennsylvania, have invented certain new and useful Improvements in Cover-Locking Ears for Pails, of which the following is a specification, reference being had therein to the accompanying drawings.

10 This invention relates to dinner-pails and other covered vessels; and the primary object thereof is to provide simple, improved, and effective means for securing the cover in place.

15 The invention consists, primarily, of a bail-ear provided with an inward extension past which the cover is adapted to move when being put in place, with the ear projection overhanging the cover in such manner as normally to prevent removal of the latter.

The invention consists, further, in so constructing the secured end of the ear that the ear, though comparatively short, may be readily sprung outward to release the cover.

25 In the accompanying drawings, Figure 1 is an elevation of a dinner-pail provided with my improvement. Figs. 2 and 3 are detail views of the improved ear. Fig. 4 is an elevation of a dinner-pail having a projecting tray and provided with elongated bail-ears constructed in accordance with my improvement. Fig. 5 is a detail perspective view of the ear shown in Fig. 4.

Referring to Figs. 1, 2, and 3 of the drawings, 2 represents the body of the pail, and 3 the combined cover and tray fitting the top thereof and formed with the usual edge flange 4, which rests on the edge bead 2' of the pail. 5 represents the bail, which is looped at its 40 extremities in the usual manner to unite with the apertured upper portions 6 of the improved ears 7. The lower portion 8 of the ear is enlarged transversely and cut away on opposite sides of the main portion 7, as indicated at 9, thus forming upwardly-projecting wings 10, which are riveted to pail-body 2 beneath top bead 2'. The main portion 7 of the ear is formed with the outward bulge 11 to pass upward around bead 2' and with 45 the inward bulge 12, immediately above bulge 11, which normally overhangs cover-flange 4 and holds the cover securely in place. The

inner face of the upper portion of bulge 12 is inclined, as shown, so that the cover may be readily positioned by moving down over 55 the ear and springing the same outward, as will be understood. The bail is so constructed as to maintain a constant inward pull upon the ears, thus acting as a spring to hold them normally drawn inward in cover-locking position. Ordinarily the metal of the ears possesses sufficient spring for this purpose; but by arranging the bail as stated the locking feature is made certain and positive.

By constructing the lower portion of the 65 ear as shown and described I am enabled to properly secure the ear adjacent the upper edge of the pail-body, and at the same time the length of the main portion 7 is sufficient to provide for outwardly springing the ear 70 when removing the cover. Also with the lower portion 8 of the ear unsecured to pail-body 2 the same has a tendency to spring or bulge outward along with the main portion 7 of the ear, as shown at 13, Fig. 3, thus augmenting the springing tendency, which is 75 very desirable in the short bail-ear of Fig. 1.

In the construction shown in Figs. 4 and 5 a projecting tray 14 is provided with a bead 14', which rests on the upper edge of the pail-body 15, and resting on tray 14 is cover 16, formed with edge flange 17. In this form of pail an elongated ear 18 is provided, which is secured at its lower end in the usual manner to the pail-body and is of sufficient length to 85 reach above the pail-cover. The ear 18 is formed with the cover-locking bulge 12, as in the construction shown in Fig. 1, said bulge overhanging the cover-flange 17 and operating in the same manner to normally secure 90 the cover in place. The ear is of sufficient length to spring outward for releasing the cover without constructing its lower end like ear shown in Fig. 2, though such construction may be used, if desired. The bail 5 of the pail 95 of Fig. 4 operates as a spring to hold the ears normally drawn inward in locking position, as described of the bail shown in Fig. 1.

While I have here shown and described the preferred adaptation of the invention, I do not 100 restrict myself thereto, as the bail-ears may be formed or provided with cover-engaging projections of many different forms without departing from the spirit and scope of the in-

vention. Though the locking devices are here shown and described in conjunction with bail-ears, it will be understood that cover-securing devices may be constructed in accordance with the invention which do not form connections for a bail.

The invention is designed, primarily, for use on dinner-pails, but may be applied with equal advantage to many other kinds of pails and vessels.

Having thus fully described my invention,

what I claim as new, and

curing ear secured to the pail, the lower extremity of the ear being enlarged or extended laterally on opposite sides with said extensions formed with the upward projections 10, the free upper portions of said projections being secured to the pail, substantially as shown and described.

3. The combination of a pail, a cover therefor, outwardly-springing bail-ears secured to the pail and
